GUSTAV PISTOR, OF LEIPZIG, AND ROBERT SUCHY, KARL STAIB, AND WILHELM MOSCHEL, OF BITTERFELD, GERMANY, ASSIGNS, BY MESNE ASSIGNMENTS, TO MAGNESIUM DEVELOPMENT CORPORATION, A CORPORATION OF DELAWARE

PROCESS FOR PRODUCING MAGNESIUM METAL BY ELECTROLYSIS

Application filed November 1, 1929, Serial No. 403,982, and in Germany February 6, 1929.

The present invention relates to a process for producing magnesium metal by electrolysis of molten chlorides.

An object of the invention is to provide for an apparatus which, when utilized for said purpose, allows one to obtain a high yield of metal and a chlorine gas of strong concentration. However, various other objects of the invention will appear from the following description without being specifically pointed out in this place.

The electrolytic production of magnesium from magnesium chloride or from a melt containing magnesium chloride may be carried out in two fundamentally different ways depending on the specific gravity of the electrolyte which may be either lighter or heavier than the magnesium metal to be separated at the cathode. The latter alternative offers the advantage that the magnesium metal which, in this case, collects on the surface of the electrolyte is entirely free from impurities. At the same time, however, considerable difficulty arises in the quantitative separation of the two products of electrolysis from each other, namely, the chlorine evolved at the anode and the magnesium metal produced at the cathode. This difficulty is aggravated when the electrolyzing current is simultaneously used for heating the bath—the latter in this case being provided with a suitable inner lining of insulating material—because on account of the increased current load of the bath comparatively larger quantities of chlorine are evolved and have to be prevented from entering the catholyte.

These electrolytic products may be separated by means of a diaphragm, which is permeable to the electric current, so as to completely divide the bath into two separate compartments. It has, however, been found that the structural coherence of all diaphragms, irrespective of the material employed, is destroyed within a short time by the intense overheating caused by the increase in resistance; thus the use of such diaphragms in practice cannot seriously be considered. A partition consisting of a mere wire-net screen, as is, for instance, frequent-

ly used in the electrolysis of sodium chloride, is likewise exposed to destruction within a short time.

Another method of separating the products of electrolysis consists in placing a solid partition of non-porous, non-conducting material between the electrodes which completely subdivides the bath to at least the depth of the electrodes themselves, both partition and electrodes extending downwards into the cell. This also results in an efficient separation of the electrolytic products. However, as the entire current is thus caused to pass below the lower edge of the partition, the resistance of the bath is increased and, incidentally, a high voltage between corresponding points on both sides of the partition ensues. Now all materials that can be used for such an insulation partition, as, for instance, fireproof ceramic materials, possess a certain, though sometimes but low, degree of porosity and, therefore, in course of time become thoroughly soaked with the electrolyte. The partition thus becomes conducting; and, owing to the high voltage drop across it, a comparatively large amount of current passes through it instead of below it, thus defeating the purpose of the partition and rapidly destroying it. The partition is most likely to be attacked at the point where it dips into the fused electrolyte. When the separated cathodically polarized magnesium comes into more or less close contact with the partition, the cathode is extended into close proximity of the partition, and also of the anode. Under these circumstances a very considerable portion of the current passes through the partition at this point, which thus becomes strongly heated. The separated magnesium when coming into contact with the hot partition repeatedly attacks its silicious constituents and reduces them, thus further accelerating its destruction.

We have now found that these corrosive effects on the partition are considerably reduced by extending the electrodes farther down into the bath to a depth considerably beyond the depth of immersion of the partition in the electrolyte. We have furthermore found that the destruction of the partition

can be almost completely prevented by immersing both electrodes into the electrolyte to such a depth that they all but touch the bottom of the bath, and so far beyond the 5 lower edge of the partition that the distance between the partition and the bottom of the bath amounts to more than double the distance from the lower edge of the electrodes to the bottom of the bath. In this case the 10 resistance of the free electrolyte below the partition is, owing to the increase of its conductive area, so much smaller than the resistance of the electrolyte taken up by the pores of the partition that the portion of the current passing through the partition becomes 15 negligible. At the same time also the voltage at corresponding points of both sides of the partition is reduced, and this also tends to diminish corrosion due to thermal or electrolytic action, which eventually ceases to 20 take place entirely.

It seems surprising that, when proceeding along the lines described above, the buoyancy 25 of the chlorine discharged at the anode in the electrolyte, the specific gravity of which is much higher, is sufficient to cause the chlorine bubbles to rise to the surface nearly vertically along the anode.

In order to completely collect the chlorine, 30 it is necessary to place the partition at a distance from the anode which increases with the depth at which the anode is immersed in the bath. When electrolyzing a charge containing molten anhydrous magnesium chloride 35 which is free particularly from carbon particles and silicic acid, the range of scattering of the ascending chlorine bubbles, owing to the viscosity of the electrolyte, is so small even at the surface that said distance 40 need only be a small fraction of the depth to which the electrodes are immersed into the bath.

We have further found that the globules 45 of metallic magnesium separated at the cathode also rise vertically to the surface of the bath in spite of the small difference between their specific gravity and that of the electrolyte. It is, therefore, possible to place the cathode very close to the partition and if, 50 by suitably tapering the lower part of the partition, a certain guidance is given to the globules towards the cathode compartment, the cathode may be even placed beneath the partition. On the other hand, the partition 55 need only be immersed in the electrolyte to such a depth that the chlorine gas is efficiently prevented from escaping into the cathode chamber.

60 By an arrangement of the partition between the electrodes according to the present invention, the destruction of the former is practically avoided. At the same time a considerably lower voltage drop is obtained 65 in the bath thus permitting the employment

of a higher amperage and, therefore, a more economical utilization of the cell.

The arrangement described above is not limited to cells of particular shape. When employing a circular cell, the cathode and the partition preferably have the shape of concentric cylinders, surrounding the rod-shaped anode placed in the centre. By placing a suitable lid or cover of non-conductive material upon the cylindrical partition in a gas-tight manner, providing a gas outlet in the lid and introducing the anode through said lid into the cell, an anode gas chamber may be constructed in a very simple manner which permits the collection and utilization of a 80 chlorine gas of high concentration.

When square or rectangular cells are employed, the partition is flat stretching across the whole width of the cell. The electrodes are preferably also flat, being for example composed, with respect to the anode, of a number of rods or flat carbons and, in the case of the cathode, of iron sheets or grate bars in juxtaposition. An anode chamber 85 may also, in the case of a rectangular cell, be easily provided by placing, in a gas-tight manner, a lid of refractory material on the rim of the partition—which for this purpose is flush with the rims of the side walls of the cell—and the three side walls of the cell surrounding the anode, and providing the chamber or cupola thus formed with a gas outlet.

Obviously, it is also possible to construct double cell units in this manner by employing a square or rectangular cell and by placing cathodes on both sides of the anode and interposing a partition between each cathode and anode. In this way a gas chamber for receiving the chlorine evolved may be formed 100 above the anode in a very simple manner, by placing, over the space between the partitions and the adjacent cell walls, a cover, preferably of the same material as employed for the partitions, and providing said cover 105 with a gas outlet. Moreover, by combining a plurality of cell elements in series so as to form a larger unit, it is possible to carry out the electrolytic production of magnesium on a large technical scale.

110 In the enclosed diagrammatic drawing there are shown, by way of example, some constructions of electrolytic double cells according to the present invention.

Fig. 1 is a vertical section of a cell and 115 Fig. 2 a ground plan of the same cell. Fig. 3 is a vertical section of a somewhat modified cell and Fig. 4 its respective ground plan. The iron vessel *a* which is provided with a refractory lining *b* surrounds the trough *c* 120 of rectangular cross-section destined to receive the electrolyte. A lid *d*, the two sides of which rest upon the rim of the receiving vessel, is provided on its outer longitudinal sides with the two partitions *e* which are 125

fitted in the wall of the receiving vessel and the lower ends of which are at a great distance from the bottom of the cell. In Figs. 1 and 2 the partitions are straight and the cathodes f_1 and f_2 are placed close to the partition. In Figures 3 and 4 the partitions are provided with extensions tapering towards the anode and the cathodes f_1 and f_2 are placed beneath the extension. The anode g is fitted 10 in the lid in a gas-tight manner and the ascending chlorine is collected in the anode chamber thus formed and is led off through an outlet h so as to be further utilized.

By virtue of the quantitative separation 15 of the products of electrolysis and the low voltages resulting from the condensed arrangement of the electrodes, as described in the present invention, besides obtaining a metal yield of 90% and more, chlorine gas 20 of 97-98% concentration may be recovered. At the same time the application of partitions as described permits the construction and employment of economical cell units on a large technical scale without requiring the 25 use of complicated and delicate structures which are never capable of efficiently resisting the mechanical or thermal influences arising in the process.

We claim:

30 1. An electrolytic cell for producing magnesium from a fused bath containing magnesium chloride, comprising a container of non-conductive material and arranged in said container a solid non-conductive substantially vertical partition and vertically disposed electrodes arranged bilaterally to said partition, said partition and electrodes extending downwards into said cell, the distance between the lower edge of said partition and the 35 bottom of the cell being more than twice the distance between either of said electrodes and said bottom.

2. An electrolytic cell for producing magnesium from a fused bath containing magnesium chloride, comprising a container of non-conductive material and arranged in said container a solid non-conductive substantially vertical partition and vertically disposed electrodes arranged bilaterally to said partition, said partition and electrodes extending downwards into said cell, the distance between the lower edge of said partition and the bottom of the cell being more than twice the distance between either of said electrodes and said bottom, and the distance between the anode and the partition being smaller than one half of the depth of immersion, in the electrolyte, of either of the electrodes.

3. An electrolytic cell for producing magnesium from a fused bath containing magnesium chloride, comprising a container of non-conductive material and arranged in said container a solid non-conductive substantially vertical partition and vertically disposed electrodes arranged bilaterally to said parti-

tion, said partition and electrodes extending downwards into said cell, the distance between the lower edge of said partition and the bottom of the cell being more than twice the distance between either of said electrodes 70 and said bottom, the distance between either of the electrodes and the partition being smaller than one half of the depth of immersion, in the electrolyte, of either of the electrodes, and the cathode being closer to the 75 partition than the anode.

4. An electrolytic cell for producing magnesium from a fused bath containing magnesium chloride, comprising a container of non-conductive material and arranged in said container a solid, non-conductive partition having a vertically arranged upper part and a lower part tapering towards the anode, a vertical anode on one side of said partition and a vertical cathode placed below said tapering, the distance between the lower edge of said partition and the bottom of the cell being more than twice the distance between either of the electrodes and said bottom, and the distance between said anode and said partition being smaller than one half of the depth of immersion, in the electrolyte, of either of said electrodes.

5. An electrolytic cell for producing magnesium from a fused bath containing magnesium chloride, comprising a container of non-conductive material and arranged in said container a solid non-conductive substantially vertical partition, an anode and a cathode, both vertically disposed and arranged bilaterally to said partition, said partition and said electrodes extending downwards into said cell, a cover contacting, in a gas-tight manner, at least with the upper rim of said partition and forming an anode gas chamber, means for withdrawing a gas from said chamber, and means for passing the anode in a gas-tight manner through said cover, the distance between the lower edge of said partition and the bottom of the cell being more than twice the distance between either of said electrodes and said bottom.

6. An electrolytic cell unit for producing magnesium from a fused bath containing magnesium chloride comprising a container of non-conductive material and arranged in said container a vertically disposed anode, two substantially vertical partitions of solid non-conductive material arranged bilaterally to said anode and extending wholly across said rectangular cell, and two vertically disposed cathodes arranged on both the outer sides of said partitions, said partitions and electrodes extending downwards into said cell, the distance between the lower edge of said partitions and the bottom of said cell being more than twice the distance between either of said electrodes and said bottom.

7. An electrolytic cell unit for producing magnesium from a fused bath containing

- magnesium chloride comprising a container of non-conductive material and arranged in said container a vertically disposed anode, two substantially vertical flat partitions of solid non-conductive material arranged bilaterally to said anode and extending wholly across said rectangular cell, a cover contacting, in a gas tight manner, with the upper rims of said partitions and the upper rims of the walls of said cell adjacent the points of issue of said partitions from said cell-walls, means for withdrawing a gas from the cupola thus formed, means for passing said anode through said cupola in a gas tight manner, and two vertically displaced cathodes arranged on both the outer sides of said partitions, said partitions and electrodes extending downwards into said cell, the distance between the lower edge of said partitions and the bottom of said cell being more than twice the distance between either of said electrodes and said bottom.
8. An electrolytic cell unit for producing magnesium from a fused bath containing magnesium chloride comprising a container of non-conductive material and arranged in said container a vertically disposed anode, two substantially vertical flat partitions of solid non-conductive material arranged bilaterally to said anode and extending wholly across said rectangular cell, a cover contacting, in a gas tight manner, with the upper rims of said partitions and the upper rims of the walls of said cell adjacent the points of issue of said partitions from said cell-walls, means for withdrawing a gas from the cupola thus formed, means for passing said anode through said cupola in a gas-tight manner, and two vertically disposed cathodes arranged on both the outer sides of said partitions, said partitions and electrodes extending downwards into said cell, the distance between the lower edge of said partitions and the bottom of said cell being more than twice the distance between either of said electrodes and said bottom, and the distance between the anode and either of said partitions being smaller than one half of the depth of immersion, in the electrolyte, of either of the electrodes.
9. An electrolytic cell unit for producing magnesium from a fused bath containing magnesium chloride comprising a container of non-conductive material and arranged in said container a vertically disposed anode, two solid non-conductive partitions, each having a vertically arranged upper part and a lower part tapering towards the anode, said partitions being arranged bilaterally to said anode and extending wholly across said rectangular cell, two vertical cathodes placed below said taperings of said partitions, a cover contacting, in a gas-tight manner, with the upper rims of said partitions and the upper rims of the walls of said cell adjacent the points of issue of said partitions from

said cell-walls, means for withdrawing a gas from the cupola thus formed, means for passing said anode through said cupola in a gas tight manner, the distance between the lower edge of said partitions and the bottom of said cell being more than twice the distance between either of said electrodes and said bottom, and the distance between the anode and either of said partitions being smaller than one half of the depth of immersion, in the electrolyte, of either of the electrodes.

10. An electrolytic apparatus for producing magnesium from a fused bath containing magnesium chloride, comprising a relatively deep electrically insulated container for said bath, a vertical anode immersed in said bath with its lower end slightly above the bottom of said container, a vertical plate-like cathode spaced from the wall of said container and immersed in said bath to substantially the same depth as said anode, and a vertical partition extending across said container between said anode and cathode, and having its lower end submerged a short distance below the surface of said bath, whereby the effective current passes directly from said anode to said cathode without passing through or around said partition.

11. An electrolytic apparatus for producing magnesium from a fused bath containing magnesium chloride, comprising a relatively deep electrically insulated container for said bath, a vertical partition extending across said container intermediate the side walls thereof, and having its lower end submerged a short distance below the surface of said bath, said submerged end being tapered, a vertical anode laterally spaced from said partition, and being immersed in said bath with its lower end slightly above the bottom of said container, a vertical plate-like cathode situated directly beneath, and slightly out of contact with the tapered end of, said partition, and having its lower end substantially in line with the lower end of said anode, whereby the effective current passes directly from said anode to said cathode without passing through or around said partition, the taper of the lower end of said partition being toward said anode to direct the globules of magnesium released at said cathode away from said anode.

In testimony whereof we have hereunto set our hands.
